JAMES LARSEN Inventor

By E. F. Bond
his Atty.

UNITED STATES PATENT OFFICE.

JAMES LARSEN, OF GREEN BAY, WISCONSIN.

TOY HANGER.

1,265,682.

Specification of Letters Patent.

Patented May 7, 1918.

Application filed July 23, 1917. Serial No. 182,318.

To all whom it may concern:

Be it known that I, JAMES LARSEN, a citizen of the United States of America, residing at Green Bay, in the county of Brown 5 and State of Wisconsin, have invented certain new and useful Improvements in Toy Hangers, of which the following is a specification, reference being had therein to the accompanying drawing.

10 The invention relates to toy hangers and has for its object the provision of a device to which a plurality of toys may be fastened for the amusement of an infant sitting in a high chair, so that a mother or nurse is free 15 to attend to household duties.

It is also an object of the invention to provide a device which may be adjusted so that the articles suspended therefrom are brought within easy reach of a child sitting in the 20 chair.

A further object aims at the provision of a device which may be conveniently placed in operative or inoperative position.

To the accomplishment of the objects 25 stated and others that will become apparent as the description proceeds, the preferred embodiment of the invention comprises the novel arrangement and construction of parts described in the following specification, specifically pointed out in the appended claims 30 and illustrated in the drawing, in which—

Figure 1 is a perspective view of a high chair to which the invention has been applied.

35 Fig. 2 is a fragmentary side view of a chair with the device in inoperative position.

In the drawing, 1 generally designates a high chair which is formed with the legs 2 and the seat 3. To the back 4 a table board 5 is pivotally secured by the arms 6, so that the table board may be swung rearwardly to permit the child to be easily placed on the chair or removed therefrom. The table board 5 at each side thereof is equipped with 40 a plate 7, which is provided with an upper horizontal flange which is notched to receive selectively the adjacent portions of a bow-like wire 8, the upper portion of which is bent in zigzag formation, so as to securely retain the cords which at their free end carry the toys provided for the entertainment and amusement of the child. As will be readily seen, a pintle 9 of the plate 7 projects through an eye at the lower end of the 45 wire, so that the wire may be turned to enter

by its resiliency in one of the notches of the plate 7, or may be swung around to assume the horizontal position shown in Fig. 2, in which position the chair is used in the ordinary manner without the toys in front of 60 the child, such as may be necessary when the child is to be fed. When it is desired to raise the board 5 so as to be placed in back of the chair, the device, of course, will participate in this movement and the toys will 65 then hang down somewhat lower than the position shown in Fig. 2.

It is obvious that instead of the wire other means may be employed for maintaining a plurality of toys in easy reach of a child sitting in a high chair, and I do not wish to be limited to the precise details shown in the drawing, but rather want to avail myself of any departures which fairly fall within the scope of the invention, as defined by the 75 appended claims.

I claim:—

1. In combination with a high chair, a bow forming a toy hanger and pivotally secured at its ends to said chair, and means 80 for permitting adjustment of said bow.

2. In combination with a chair, a bow forming a toy hanger and pivotally secured at its ends to said chair, said bow being of sufficient size to clear the back of said chair 85 when being swung in inoperative position, and means for adjustably maintaining said bow in operative position.

3. In combination with a high chair having a table board pivotally secured to its 90 back, a bow forming a toy hanger and pivotally secured at its ends to the sides of the table board, said bow being of sufficient size to clear the back of the chair when being swung in inoperative position, and a notched 95 plate adapted to receive the side of said bow.

4. In combination with a high chair having a table board pivotally secured to its back, a resilient bow forming a toy hanger and pivotally secured at its ends to the sides 100 of the table board, said bow being of sufficient size to clear the back of the chair when being swung in inoperative position, and a notched plate arranged at the side of the table board, said bow entering one of the 105 notches of said plate.

In testimony whereof I hereunto affix my signature.

JAMES LARSEN.
